[57] CLAIM

The ornamental design for a combined stadium storage pocket and cushion, as shown and described.

DESCRIPTION

FIG. 1 is a top, front, and left side perspective view of a combined stadium storage pocket and cushion showing my new design;

FIG. 2 is a top, front, and left side perspective view thereof, showing the article in a closed configuration;

FIG. 3 is a front elevational view thereof;

FIG. 4 is a rear elevational view thereof;

FIG. 5 is a right side elevational view thereof, the left side being a mirror image of that shown;

FIG. 6 is a top plan view thereof; and,

FIG. 7 is a bottom plan view thereof.
